ALBERT H. DE VOE, OF WESTFIELD, NEW JERSEY, ASSIGNOR TO THE SINGER MANUFACTURING COMPANY, OF ELIZABETH, NEW JERSEY, A CORPORATION OF NEW JERSEY.

FEEDING MECHANISM FOR SEWING MACHINES.

Application filed March 20, 1920. Serial No. 367,556.

To all whom it may concern:

Be it known that I, ALBERT H. DE Voe, a citizen of the United States, residing at Westfield, in the county of Union and State 5 of New Jersey, have invented certain new and useful Improvements in Feeding Mechanisms for Sewing Machines, of which the following is a specification, reference being had therein to the accompanying drawings.

10 This invention relates to sewing machines and particularly to feeding mechanisms therefor in which differentially actuated members are moved to gather or full fabric in advance of the presser foot in order that 15 it may be subsequently sewed in either a ruffled or a substantially normal condition, free from distortion or stretch, according to the character of the work.

It has for its object to provide an improved high speed differentially movable feeding mechanism which is simple in construction, compact, readily adjustable and quick acting.

20 A further object of the invention is to provide mechanism for imparting four motions to an upper feeding member from a single driving shaft and through connections that permit the lengths of the feeding and lifting strokes thereof to be varied, to provide means 25 acting independently of the presser-foot for urging the upper feeding member against the fabric and to provide an adjustable means or stop to prevent the auxiliary feeding element from coming in contact with the 30 teeth of the main feed-dog at such time as the material being stitched may pass out from under the presser-foot.

It is also an object of the invention to provide a lost motion connection between the 35 auxiliary feeding member and the presser-foot so that when the latter is raised for the removal of work the auxiliary member will be raised also, but which during normal operation as the presser-foot is raised by inequalities in the work will not raise the auxiliary feeding member from engagement 40 with the work.

And another object of my invention is to provide in a differential feeding mechanism

50 automatic means whereby the drag of the presser-foot on the work may be compensated for and upper and under plies of material fed uniformly, regardless of the work's thickness.

These and other objects are realized in my 55 present construction in which preferably a needle-driving rock-shaft is provided with a crank-disk, having a tapering circular opening, within which fits a spring-pressed frusto-conical member which is thus driven 60 through frictional engagement therewith. The frusto-conical member is preferably provided with a roller-stud having driving connection with a pivoted feed-blade carrying arm, fulcrumed on a hanger from which 65 the feeding movements of the blade are derived through a connection with a pivotally adjustable crank-element on the crank-disk. The hanger is fulcrumed on a supporting lever which is in turn fulcrumed on the 70 frame of the machine. This hanger has an adjustable connection with the presser-foot lifting mechanism, and there is a yielding means provided which tends to turn this lever about its fulcrum to maintain the blade 75 in contact with the work during its feeding movements. Adjustable stops are provided for limiting the lifting movements of the blade.

The present improvement in its broad aspects is related to the invention disclosed in my copending application Serial No. 132,521, filed Nov. 21, 1916.

80 My invention also consists in certain details of construction which are illustrated in 85 the embodiment shown in the drawings in which Fig. 1 is a front elevation of the head of the machine showing my feeding mechanism in position. Fig. 2 is a view similar to Fig. 1 with the face-plate and certain 90 elements of the feeding mechanism removed. Fig. 3 is a sectional elevation substantially on the line 3—3 of Fig. 1. Fig. 4 is an elevation of the rear side of the face-plate. Fig. 5 is a detailed perspective of certain 95 elements of the drive for the auxiliary member. Fig. 6 is a perspective of the forward end of the main driving shaft.

The embodiment of the machine illustrated comprises an overhanging head 1 of the machine in which is mounted a presser-bar 2 at the lower end of which is the 5 presser-foot 3. Mounted on the presser-bar and adjustably secured thereto by a set screw 4 is a block 5. 6 is a yoke having sliding connection with the presser-bar on opposite sides of the block 5 as shown and is provided 10 with a cut away portion 7 to allow for a certain movement of the presser-bar without imparting movement to the yoke. Fulcrumed in the head of the machine at 8 is an ordinary hand lifting cam 9 contacting 15 with a roller-stud 10 mounted on the yoke 6 through which the presser-bar and presser-foot may be raised for the insertion and removal of work in the usual manner. The block 5 has extending from the rear thereof 20 a portion 11 in which is mounted the rod 12 having sliding engagement in the bearing 13 in the head 1 to prevent turning of the presser-bar. The upper part of the extension 11 is provided with a slot 14 in which is 25 fitted the roller-stud 15 mounted in the end of the crank 16 pivoted in the head 1 at 17 and to which is secured the usual connection from an ordinary foot-treadle, not shown, for lifting the presser-foot. Mount- 30 ed on the overhanging arm of the machine is a spring 18 bearing on the upper end of the presser-bar 2 to hold the presser-foot down upon the work.

Also mounted in the head 1 is the needle-bar 19 which is reciprocated by crank 20 driven from an oscillating shaft 21. Secured to the lower end of the needle-bar is a needle-clamp 22 for sustaining the needles 23 in any desirable manner.

10 Adapted to extend through the throat-plate 24 and to cooperate with the lower side of the presser-foot 3 for feeding the work in the usual manner, is the feed-dog 25.

The mechanism so far described is com- 45 mon and well known.

Also mounted on the main-shaft 21 is a crank 26 provided with a groove 27 in which is mounted the shank 28 of a driving mem- 50 ber 29. The shank 28 is secured to the crank 26 by means of screws 30 or by any other suitable means. The member 29 is prefer- 55 ably formed as a disk as shown, in the center of which and in alinement with the axis of the shaft 21 is provided a tapered opening 31. The shaft 21 is rocked or oscillated by means of any suitable driving mecha- nism.

Secured to the front of the head is the face-plate 32 the lower portion of which is 60 covered by the plate 32' secured thereto by suitable screws 32''. Mounted in the plate is a bearing 33 provided with a flange 33' whereby it may be secured to the plate by means of the screws 34. The bearing 33 is 65 preferably a tubular member in the bore of

which at its outer end and having screw threaded engagement therewith is a sleeve 35, which may be secured in adjusted position by a lock-nut 35'. Also mounted with- 70 in the bore of this bearing 33 at the inner end is the shank 36 of a driven member 37. This shank is reduced at 38 so as to slide within the opening 39 in the sleeve 35 and to form a shoulder with the body of the shank 36 and surrounding the reduced portion 38 75 and between the shoulder and the sleeve 35 is a spring 39'. The driven member 37 is pro- 80 vided with a frusto-conically shaped boss 40 adapted to fit within the tapered opening 31 in the driving element or disk 29. The bearing 33 is formed separately from and adjustably mounted on the face-plate 32 for convenience in manufacture, this facilitating alinement of the driven member 37 with re- 85 spect to the driving member 29.

Mounted in a groove or channel 41 in the face-plate 32 are two adjustable stops 42 and 43. The driven member 37 is provided with a lateral extension 44 on which is mounted a block 45 which when the driven 90 member 37 is oscillated moves between the opposed ends of the stops 42 and 43. The driven member 37 is also provided with a lateral extension 46 which is provided with a roller-stud 47.

On the rear face of the driving member 29 is the adjustable plate 50 which is pivoted to the member at 51 and at the upper end is provided with a screw 52 extending through a slot 53 formed in the disk 29 diagonally 100 opposite the fulcrum 51. By tightening this screw 52 the plate 50 is held in adjusted position. The plate 50 is also provided with a stud 54 upon which is pivotally mounted the block 55.

The auxiliary feed member comprises a blade 56 mounted to engage the upper side of the work in advance of the stitching mechanism. My device is however not lim- 110 ited to use with a feeding member but is equally adapted for use with a ruffling, full- 115 ing or shirring blade. This blade is formed with a shank 57 and a portion 58 bent at right angles thereto on the lower end of which is formed a series of teeth for engag- 120 ing the work. The shank 57 is secured by means of a screw 59 to a block 60 and also by means of a screw 61 to a lever 62. The lever 62 is in turn fulcrumed at 63 on a feed-car- 125 rier or hanger 64 which is fulcrumed at 65 to a supporting lever 66 fulcrumed at 67 on the head of the machine. The supporting member or hanger 64 at its lower end has a projection 68 spaced forwardly of the portion in which the fulcrum 63 is located and is provided with a guiding member 69 se- 130 cured thereto by means of the screws 70. The block 60 on the shank 57 has a reduced portion adapted to be guided between the member 69 and portion 68 of the hanger 64. 130

The upper end of the hanger 64 is forked as shown at 71 and embraces the block 55 on the rear face of the driving member 29. The supporting lever 66 is provided with a channel 72 in which is adjustably secured a member 73 having an overhanging portion 74 at its upper end. The lower edge of this overhanging portion is during normal operation extended over the roller stud 10 by which the presser-bar is lifted as clearly shown in Fig. 2. It is, however, normally not in contact with this roller-stud so that the presser-foot may lift a certain amount due to inequalities in the work without affecting the auxiliary feeding member. The member 73 is adjustably secured to the lever 66 by means of screws and slots 75. The fulcrum 67 of the supporting lever 66 extends through a bearing in the head of the machine and is provided at the end opposite the lever 66 with a crank 76 provided with a roller stud 78. Tending to turn the fulcrum 67 through the crank 76 and roller-stud 78 is a spring 79 which has an abutment against the head of the machine at its central portion and at its upper end is mounted on the stud 79'. 80 is a thumb screw by which the pressure of the spring may be adjusted in a well known manner.

30 The connection at 65 between the hanger 64 and the supporting lever 66 comprises the pin 81 secured to the hanger and extending through a bearing lug 82 on the lever 66, and it is provided with a collar 83 which 35 may be secured to the end thereof by a set screw to retain the pin 81 in the bearing 82.

The lever 62, to the lower end of which the shank 57 of the auxiliary feeding member 56 is secured, is provided at its upper end 40 with a fork 84 embracing the roller-stud 47 on the driven member 37.

In operation the shaft 21 is oscillated through any suitable driving mechanism. This oscillation reciprocates the needle-bar 45 and the needles 23 in a well known manner. As the driving member 29 is also secured to the shaft 21 it oscillates therewith and through frictional engagement with the frusto-conical boss of the driven member 37 oscillates this member also. The oscillation of the member 37, however, is limited by contact of the block 45 with the adjustable stops 42 and 43. By adjusting these stops higher or lower on the face-plate or 55 nearer together or farther apart the amount of the oscillation of the driven member 37 may be varied and also the angular position of this member about its axis. As this member through the stud 47 and lever 62 imparts 60 the lifting movements to the auxiliary feeding member 56, it is clear that these adjustments regulate the position and amount of lifting movement of this auxiliary feeding member. The pressure of the frusto-conical boss 40 against the walls of the ta-

pering opening 31 in the driving disk or member 29 may be adjusted by screwing the sleeve 35 outwardly and inwardly in the bearing member 33 thus varying the pressure on the spring 39'. After the sleeve is 70 adjusted it may be secured in adjusted position by lock-nut 35'.

Feeding movements are imparted to the auxiliary feed member 56 by oscillation of the supporting member or hanger 64 about 75 its fulcrum 65 on the supporting lever 66. This member 64 is oscillated from the adjustable plate 50 on the rear of the oscillating disk or driving member 29 through the block 55. It will be clear from an inspection of Fig. 2, which shows the needle at its highest point, that the plate 50 may be adjusted about the screw 51 as a center, thereby carrying the stud 54 toward or away from the axis of the rock-shaft 21 in a direction 80 substantially at right angles to the length of the slot in the lever 71. This adjustment permits the feeding stroke of the feeding member 56 to be varied without appreciably affecting the timing of the prolonged dwell 85 of such feeding member which occurs at the end of its feeding stroke and during the first part of the down stroke of the needle or needles, whereby the fulled work is held 90 until it is entered by the needle or needles. 95

In sewing position when work is passing between the presser-foot and main feed-dog 25, the member 73 is adjusted in the supporting lever 66 so that the overhanging portion 74 is spaced above the roller-stud 100 10. This allows the presser foot to be raised a certain distance when passing over small humps or ridges in the work without raising the auxiliary feeding member 56. It will thus be seen that this is in effect a lost motion 105 connection between the supporting means for the auxiliary member and the presser-foot and will allow the presser-foot to rise under the action of small ridges etc., in the work without raising the auxiliary member from 110 in contact therewith, but should the presser-foot be raised for the insertion and removal of work the auxiliary feeding member will be raised also. The member 73 is, however, so adjusted in the supporting lever 115 66 that should the work pass out from under the presser-foot the action of the spring 79 will not force the teeth of the auxiliary member 56 into contact with the teeth of the main feed-dog 25. This is because in such an event the lower edge of the overhanging portion 74 comes in contact with the upper side of the stud 10 and thus supports the auxiliary member 56 and its supporting mechanism. 120

125 It will also be noted that as the lifting movements are imparted to the member 56 by means of a stud 47 on the member 37 through the fork 84, that should the presser-foot be lifted and with it the hanger 64 and 130

driving lever 62, this connection assures perfect freedom for them to rise and fall irrespective of the friction driving mechanism.

It will further be seen that the spring 79 provides a yielding means acting independently of the presser-foot and its spring 18 to urge the auxiliary member into contact with the work.

It is to be distinctly understood that the invention is not limited to the specific construction shown and described, as the same is merely the preferred form of the invention as now appears to me.

Having thus set forth the nature of my invention what I claim herein is:—

1. In a sewing machine, in combination with a stitching mechanism, a fulling feed having a fabric engaging element arranged for operation on fabric in advance of the stitching mechanism, means for imparting four motions to said fabric engaging element including a friction-driving connection comprising an oscillating member provided with a tapering opening and a frusto-conical member yieldingly pressed into engagement with the walls of said opening.

2. In a sewing machine, in combination with stitching mechanism a feeding member, means for operating the feeding member comprising a rock-shaft, a disk mounted to oscillate therewith and provided with a tapering opening, a yieldingly mounted member adapted to coact with said tapering opening and means connecting said yieldingly mounted member and the feeding member.

3. In a sewing machine, in combination with the stitching mechanism, a feeding element, an oscillating driving member, means connecting the driving member with the feeding element for imparting feeding movements thereto, a driven member having frictional driving engagement with said driving member, and means connecting the driven member with the feeding element independently of the driving member to impart lifting movements to said feeding element.

4. In a sewing machine, in combination with the stitching mechanism, a feeding element, an oscillating driving member, a driven member having frictional driving engagement with said driving member, means whereby feeding movements are imparted to the feeding element from one of said members and means connected to the other member independently of the first member whereby lifting movements are imparted to said feeding element from the said other member.

5. In a sewing machine, in combination with the stitching mechanism, a feeding element, an oscillating driving member, a driven member having frictional driving engagement with the first member and means

connected with the driven member independently of the driving member for imparting movements from the driven member to the feeding element.

6. In a sewing machine, in combination with the stitching mechanism, a feeding element, an oscillating driving member, a driven member having frictional driving engagement with the first member, means connected with the driven member independently of the driving member for imparting movements from the driven member to the feeding element, and adjustable stop means for limiting the movements of the driven member.

7. In a sewing machine, in combination with the stitching mechanism, a feeding element, an oscillating driving member, a driven member having frictional driving engagement with the first member, means for imparting movements from the driven member to the feeding element and yielding means for urging the feeding element into engagement with the work.

8. In a sewing machine, in combination with the stitching mechanism, a feeding element, an oscillating driving member provided with a tapered opening, a driven member provided with a frusto-conical portion, means for retaining the frusto-conical portion in frictional driving engagement with the walls of said opening, and means for transmitting movement from the driven member to the feeding element.

9. In a sewing machine, in combination with the stitching mechanism, cooperating presser and feeding elements for the work to be stitched, an auxiliary feeding element adapted to engage the work in advance of the stitching mechanism, means for supporting and operating the auxiliary feeding element including a lever fulcrumed on the frame of the machine, a lost motion connection between the lever and the presser element and yielding means acting through said lever to urge the auxiliary feeding element against the work.

10. In a sewing machine, in combination with the stitching mechanism, cooperating presser and feeding means for the work to be stitched, an auxiliary feeding element adapted to engage the work in advance of the stitching mechanism, operating means therefor comprising an oscillating driving member, a driven member having frictional driving engagement with the driving member, a supporting lever fulcrumed on the frame of the machine and having lost motion connection with the presser element, means pivoted to the supporting lever and connected with the driving element for transmitting movement to the auxiliary feeding element, means connected with the driven member independently of the driving member for transmitting movement from

the driven member to the auxiliary feeding element and yielding means acting through the supporting lever to urge the auxiliary feeding element against the work.

5 11. In a sewing machine, in combination with stitch-forming mechanism, a fulling feed having a fabric engaging element arranged for operation on fabric in advance

of the stitch-forming mechanism, means for imparting feeding and lifting movements to said element including a friction-drive connection and means for causing a prolonged dwell at the end of the feeding movements.

In testimony whereof, I have signed my name to this specification.

ALBERT H. DE VOE.
